UNITED STATES PATENT OFFICE

GUSTAV F. HOCHRIEM, OF CHICAGO, ILLINOIS

DESIGN FOR A CABINET FOR COIN CONTROLLED APPARATUS

Application filed June 27, 1932. Serial No. 44,205. Term of patent 14 years.

To all whom it may concern:

Be it known that I, GUSTAV F. HOCHRIEM, a citizen of the United States, residing at Chicago, in the county of Cook and State of Illinois, have invented a new, original, and ornamental Design for a Cabinet for Coin Controlled Apparatus, of which the following is the specification, reference being had to the accompanying drawings, forming part thereof.

In the drawings:—

Figure 1 is a front view of the cabinet showing my new design;

Fig. 2 is a top view of the same;

Fig. 3 is a side view on a reduced scale, and

Fig. 4 is a back view on a reduced scale.

I claim:—

The ornamental design for a cabinet for coin controlled apparatus as shown.

In testimony whereof, I affix my signature.

GUSTAV F. HOCHRIEM.
